ARTHUR F. HICKIE, OF LANSING, MICHIGAN.

DOORCHECK.

Application filed April 20, 1926. Serial No. 103,290.

This invention relates to door checks of the invertible type, and has for its object the production of a cheap and very strong door holder having parts of special construction and arrangement, and which may be easily and conveniently operated by the foot entirely without the use of the hands.

The special construction and arrangement of the parts of this invention are illustrated in the accompanying drawings of which Fig. 1 represents a door shown edgewise and having this invention applied thereto in holding position. Fig. 2 is a like view of a door with this invention inverted and drawn in its vertical position against the door. Fig. 3 is a cross-section on the line 3—3 of Fig. 1.

Throughout the drawings and this explanation the same number is used to refer to the same part.

Considering the drawings, a door 1 has thereon a keeper 2 provided with a back plate 3 secured to the door in any manner, as by the screws 4. The keeper has projecting ears through which pass a pivot bolt 5.

Referred to generally by the numeral 6 is a single piece of sheet metal bent upon itself to form the body of the check which is hollow. From the end of the piece of metal on one side are the turned in shorter flanges or walls 7, and from the end of the piece on the other side are the longer turned in flanges 8.

At the lower end of the hollow body is secured the non-metallic floor-engaging foot 9.

The ends of the flanges 7 and 8 are the projecting stop members alternately brought into contact or engagement with the pivot bolt 5. That is to say, when the body 6 is inverted against the door 1 the end 10 of the shorter flanges 7 rests on the pivot bolt 5, but when the check is in operating position with the foot upon the floor, the tops 11 of the flanges 8 press against the bolt.

The construction described leaves at one side of the body a longitudinal opening 12, and this opening is closed at the top by the bend of the metal piece, and engages the bolt 5 as illustrated. The opening enables the body to be slipped up and down upon the bolt 5.

In the operation of this invention, assume the body to be in its vertical position against

the door as shown in Fig. 2. A slight upward pressure by the foot on the bent end of the metal piece raises the whole until the bolt occupies the rounded and bent end. Now, the body becomes overbalanced and the end having the foot 9 falls into contact with the floor. The body assumes an inclined position as illustrated, and if the door is pulled or wind blown the bolt and the upper ends of the longer flanges meet, and no further movement of the door can take place. Obviously, a suitable movement by the foot of the operator will turn the body up against the door again. As many modifications can be readily made in the parts of this invention, it is not intended that anything in this description shall limit the structures to the forms shown.

Having now described this invention and its operation, what I claim is:—

1. An invertible door check, comprising a single piece of metal bent upon itself to form a hollow body, a non-metallic floor-engaging foot secured in the lower end of the body, said body having shorter flanges on one side and longer flanges on the other side leaving an opening lengthwise at the side of the body, in combination with a keeper secured to a door and having a pivot bolt engaging the said side opening of the said body whereby when the said foot engages the floor the tops of said longer flanges engage the said pivot bolt of the keeper, and when the said body is inverted the ends of the said shorter flanges encounter the said bolt.

2. An invertible door check, comprising a body portion, a floor-engaging foot secured in the lower part of the said body, a keeper secured to a door and having a pivot bolt, said body having an opening lengthwise at the side extending to the top of the body and closed at the top and engaging the said bolt, said body having two contact members, one of said members being located at said closed top of said opening on one side of the body and the other member at the lower end of the said opening on the other side of the body whereby when said foot engages the floor the top contact member engages the pivot bolt, and when the said body is inverted the lower of the said members engages the pivot bolt.

3. An invertible door check, comprising a single piece of sheet metal formed with pairs of flanges extending towards each other and forming a hollow body, one pair of flanges being longer than the other pair leaving a longitudinal opening through the said body, a support having a pin arranged to engage

the said opening and to meet the top of the longer flanges when the check is in operative position, and a floor contact foot secured in the end of the said body. ¹⁰

In testimony whereof I affix my signature.

ARTHUR F. HICKIE.
